UNITED STATES PATENT OFFICE.

HENRY G. VOIGHT, OF NEW BRITAIN, CONNECTICUT.

DOOR-CONTROLLING MEANS.

1,058,679.

Specification of Letters Patent.

Patented Apr. 8, 1913.

Application filed November 20, 1912. Serial No. 732,403.

To all whom it may concern:

Be it known that I, HENRY G. VOIGHT, a citizen of the United States, residing at New Britain, Hartford county, State of Connecticut, have invented certain new and useful Improvements in Door-Controlling Means, of which the following is a full, clear, and exact description.

This invention relates to sliding doors of the type wherein a movable arm is carried by the door and is operatively connected with a power closing mechanism which normally tends to move said arm in a direction to move the sliding door to closed position, suitable operating means being provided for moving said arm to move the door to opened position.

The present invention aims to provide means for blocking the operation of the closing mechanism so that the door may be locked in opened position. This and other advantages are described in detail in the following specification and are illustrated in the accompanying drawings forming part thereof and showing a preferable embodiment of the invention.

In these drawings: Figure 1 is a view in elevation of the sliding door of an elevator well equipped with door closing mechanism of the character described, and provided with my blocking device operating in conjunction therewith. Fig. 2 is a fragmentary view in elevation of the closer cylinder with one form of blocking device mounted thereon and in operative blocking position. Fig. 3 is a similar view showing the blocking device in inoperative position. Fig. 4 is a fragmentary view in elevation of the door controlling parts and closing mechanism in door opened position. Fig. 5 is a top plan view of the closer cylinder showing the blocking device applied thereto. Fig. 6 is a top plan view of the friction clamp. Fig. 7 is a top plan view of the actuating cam therefor. Fig. 8 is a view in elevation illustrating a modified form of blocking device. Fig. 9 is a fragmentary view in elevation with the door controlling parts in door opened position and the modified form of blocking device in operative blocking position. Fig. 10 is a top plan view of the parts shown in Fig. 9. Fig. 11 is a detail in front and edge elevation of the blocking plate.

55 Referring to the drawings by numerals:

1 indicates the sliding door of an elevator well and 2 the casing thereof.

3 designates a lever arm pivotally mounted at its forward end upon the forward edge of the door 1 and having its rear end 60 pivotally connected to a second lever arm 4, which in turn is pivotally carried at its rear end by a bracket 5, which bracket is secured to the casing of the elevator door which forms an abutment stationary relatively to the door. The lever arm 4 adjacent its bracket-pivoted end is provided with a transverse extension 6 to which is journaled a piston rod 7 of a closer cylinder 8, which cylinder may be of the type employing a coiled spring acting against the head of the piston rod 7 and normally tending to pull the lever arm 4 downwardly and through said arm and lever arm 3, move the sliding door 1 to closed position. The 75 forward end of the lever arm 3 is pivotally mounted on a plate 9 fixedly carried on the forward edge of the sliding door. In order to open the door against the force of the closing mechanism, an operating lever 10 80 is provided pivotally mounted at its upper end upon the door. An operating arm 11 is likewise pivotally mounted at its upper end upon the door and is provided with a curved slot 12 therein in which rides a pin 13 85 carried by the lever arm 3 adjacent its forward pivoted end, this curved slot 12 having the function of a cam. The operating handle 10 has projecting from its under face a stud 14 which, when the door is in closed position, 90 rests against the forward edge of the arm 11. When it is desired to open the door, the handle 10 is moved to the right from the position shown in Fig. 1, this movement, through its stud 14, lifting the arm 11, and 95 through its cam slot 12, raising the lever members 3 and 4 and starting the door on its opening movement. By the time these levers have been so moved, the edge of the operating handle 10 will have engaged the 100 abutment stud 15 carried by the door plate 9, and further and continued pull on the handle 10 in the same direction will move the sliding door 1 to opened position, the transverse extension 6 of lever arm 4 swinging upwardly and pulling with it the piston rod 7 of the closing mechanism against the force of the spring or other power within the closing cylinder.

The head of the closer cylinder 8 is formed 110

with a boss 16 and a cam ring 17 is seated over the upper face of this boss and about the piston rod 7. This ring 17 is provided with a concentrically offset cam edge 18 at 5 one side thereof and with a finger piece 19 projecting from the opposite side thereof. The boss 16 is provided at one edge with spaced ears 20 between which is pivotally mounted one end of a frictional locking 10 plate 21 fitting over the piston rod 7 and resting upon the upper face of the cam ring 17. The aperture in this locking plate 21 is just slightly greater in diameter than the piston rod 7 and allows the piston rod to 15 slide freely therethrough under normal conditions, the free end of said friction locking plate being normally pressed down upon the flat upper face of the cam ring 17 by means of a spring 22 secured to the boss 16 of the 20 closer cylinder. In the normal inoperative position of this locking plate 21, the cam edge 18 of the cam ring is out of contact with the under side of the locking plate, as shown in Fig. 5 of the drawings. Assuming, however, that it is desired to lock the 25 door open to any degree, the operating handle 10 is actuated to move the door open to the required degree, whereupon the finger piece 19 of the cam ring 17 is moved to 30 bring the cam edge 18 beneath the locking plate 21. This will raise the hinged locking plate 21, causing its edges adjacent the aperture therein to bite against the piston rod 7 and frictionally lock the same against door 35 closing movement (see Fig. 2). In order to release the piston rod and allow the door to close, it is only necessary to move the finger piece 19 of the cam ring in the opposite direction, moving its cam edge from beneath 40 the pivoted locking plate and permitting the spring 22 thereof to move said plate downwardly to inoperative position, as shown in Fig. 3 of the drawings.

It will be obvious from the foregoing that 45 the closing mechanism may be blocked against door closing operation at any point of door opening movement so that the degree to which the door is held open may be regulated at will. Furthermore, by it, the 50 door may be absolutely locked closed.

In Figs. 8-11 of the drawings, I have illustrated a modified form of blocking device operative only, however, to block the closing mechanism against operation with the door 55 fully opened, or substantially so. This modified form of blocking device comprises a plate 24 pivoted to the lower end of the transverse extension 6 of lever arm 4, as at 23, and having its lower edge 25 formed 60 eccentrically to its pivot 23. Secured to one edge of the plate 24, preferably adjacent its eccentric lower edge, is a clip 26 having a hooked end 27 which, when the locking plate 65 is in inoperative position, engages the upper edge of the lever arm 4 and is held thereby

against movement. When the door is moved to fully opened position, or substantially so, the plate 24 may be released from the lever arm 2 and swung downwardly to bring its eccentric edge against the boss 16 formed on the upper face of the closer cylinder, thereby preventing downward movement of the piston rod 7 to move the lever arms 3 and 4 in a direction to close the door. The length of the plate 24 is, of course, figured to bring its eccentric or cam edge into frictional blocking contact with the upper face of the closer cylinder when the lever arm 4 and its transverse extension 6 have been moved to door opened position. By forming the contact or blocking edge of the blocking plate 24 eccentrically to its pivot, I am enabled to allow for any slight variation in the door opening movement of the lever arm 4 and its transverse extension, the eccentric edge of the blocking plate forming a sort of compensating means. It will be, of course, obvious that in order to release the parts and permit the closing mechanism to move the door to closed position, it is only necessary to move the blocking plate 24 from engagement with the upper face of the power cylinder, whereupon the closing mechanism will become operative to close the door. The blocking plate, as before stated, is secured to the upper edge of the lever arm 4 by means of its clip 26, when not in use.

While I have described herein specific embodiments of my invention, I desire it understood that the structure thereof is subject to modification within the spirit of the invention and scope of the appended claims.

What I claim, therefore, and desire to secure by Letters Patent is:

1. In a device of the character described, 10. in combination, a sliding door, a relatively stationary abutment, a movable arm carried by said door operatively connected with said abutment to move with the opening and closing of the door, closing mechanism operatively connected with said arm to move the same in a direction to close said door, operating means for moving said door to open position, and means co-operating with said closing mechanism to render the same 110 inoperative to move said door to closed position.

2. In a device of the character described, 120 in combination, a sliding door, a relatively stationary abutment, a movable arm carried by said door operatively connected with said abutment to move with the opening and closing of the door, closing mechanism operatively connected with said arm to move the same in a direction to close said door, operating means for moving said door to open position, and means co-operating with said closing mechanism to render the same 125 inoperative to move said door to closed position at different points of door opening position. 130

3. In a device of the character described, in combination, a sliding door, a relatively stationary abutment, a movable arm carried by said door operatively connected with 5 said abutment to move with the opening and closing of the door, closing mechanism operatively connected with said arm to move the same in a direction to close said door, operating means for moving said door to 10 open position, and manually controlled means coöperating with said closing mechanism to lock the same against operation to move said arm to close said door.
4. In a device of the character described, 15 in combination, a sliding door, a relatively stationary abutment, a movable arm carried by said door operatively connected with said abutment to move with the opening and closing of the door, closing mechanism for 20 said door embodying a power cylinder and a piston rod therein operatively connected with said movable arm to move the same in a direction to move said door to closed position, operating means for moving said 25 door to open position, and means for locking said piston rod against movement.
5. In a device of the character described, 30 in combination, a sliding door, a relatively stationary abutment, a movable arm carried by said door operatively connected with said abutment to move with the opening and closing of the door, closing mechanism for 35 said door embodying a power cylinder and a piston rod therein operatively connected with said movable arm to move the same in a direction to move said door to closed position, operating means for moving said 40 door to open position, and manually operable means for locking said piston rod against door closing movement.
6. In a device of the character described, 45 in combination, a sliding door, a relatively stationary abutment, a movable arm carried by said door operatively connected with said abutment to move with the opening and closing of the door, closing mechanism for 50 said door embodying a power cylinder and a piston rod therein operatively connected with said movable arm to move the same in a direction to move said door to closed position, operating means for moving said 55 door to open position, and manually operable means for locking said piston rod against movement, said means including a cam member coöperating with said cylinder and piston rod.
7. In a device of the character described, in combination, a sliding door, a relatively stationary abutment, a movable arm carried by said door operatively connected with 60 said abutment to move with the opening and closing of the door, closing mechanism for 65 said door embodying a power cylinder and a piston rod therein operatively connected with said movable arm to move the same in a direction to move said door to closed position, operating means for moving said door to open position, and manually controlled means adapted to engage and frictionally hold said piston rod against movement. 70
8. In a device of the character described, 75 in combination, a sliding door, a relatively stationary abutment, a movable arm carried by said door operatively connected with said abutment to move with the opening and closing of the door, closing mechanism for 80 said door embodying a power cylinder and a piston rod therein operatively connected with said movable arm to move the same in a direction to move said door to closed position, operating means for moving said door to open position, and manually controlled means adapted to engage and frictionally hold said piston rod against movement, said means including a movable friction plate, and manually controlled means for moving said plate into frictional locking engagement with said piston rod. 85
9. In a device of the character described, 90 in combination, a sliding door, a relatively stationary abutment, a movable arm carried by said door operatively connected with said abutment to move with the opening and closing of the door, closing mechanism for 95 said door embodying a power cylinder and a piston rod therein operatively connected with said movable arm to move the same in a direction to move said door to closed position, operating means for moving said 100 door to open position, and manually controlled means adapted to engage and frictionally hold said piston rod against movement, said means embodying a movable friction plate carried by said power cylinder 105 and a coöperating cam member manually operable to move said plate into frictional locking engagement with said piston rod.
